UNITED STATES PATENT OFFICE.

HENRY PARSONS, OF MARLBOROUGH, MASSACHUSETTS.

MACHINE FOR CUTTING LEATHER OR OTHER MATERIALS.

SPECIFICATION forming part of Letters Patent No. 368,103, dated August 9, 1887.

Application filed April 27, 1887. Serial No. 236,288. (No mod. 1.)

To all whom it may concern:

Be it known that I, HENRY PARSONS, of Marlborough, in the county of Middlesex and State of Massachusetts, have invented a new and useful Improvement in Machines for Cutting Leather or other Materials, which will, in connection with the accompanying drawings, be hereinafter fully described, and specifically defined in the appended claims.

10 Figure 1 is a front elevation of a machine embodying my invention. Fig. 2 is an end elevation taken as from the right in Fig. 1. Fig. 3 is also an end elevation taken as from the left in Fig. 1. Fig. 4 is a longitudinal vertical section taken on line Y Y, Figs. 2, 3, 15 5, and viewed from the same position as in Fig. 1, or from the left in Fig. 2 and from the right in Figs. 3 5. Fig. 5 is a transverse vertical section taken on line Z Z, Fig. 1, and as 20 on the same line in Fig. 4, and viewed as from the left in each of said figures. Fig. 6 is a rear elevation—that is, taken from the opposite from Fig. 1, and as viewed from the right in Fig. 2 and from the left in Figs. 3 and 5.

25 My invention relates to that class of leather-cutting power-driven machines termed "beam cutters" or "beam cutting-machines," or "beam cutting-presses" in which the sides of leather or sheets of leather-board or other material to be cut are spread out upon a cutting-block supported by a bed that is vertically adjustable, such material being cut by a die that is free to be placed by the operator in a new position after each cut, the die being forced 30 through the material by a beam arranged above the bed, and which is vertically reciprocated to effect such result; and it consists in features of novelty hereinafter fully described, and pointed out in the claims.

40 Referring again to the drawings, A A represent the end frames or standards, the form and function of which will, from an inspection of the drawings and their necessary description in connection with the other parts of the machine, be clearly understood. Said end frames are rigidly secured together in proper relative position by the front girt, B, and rear girt, C, which at their respective ends are bolted to said standards, as shown in Figs. 1, 2, 3, 6. 45 50 The bed D is supported and vertically adjusted at each end by screw-rods a, actuated by hand-wheels b and having their lower ends

seated in conical cavities in frames A, as shown in Fig. 4. On each said rod is threaded the nut c, on which is seated the tubular end 55 d of bed D; hence by actuating said screws in the proper direction the bed may be raised or lowered in the well-known manner.

The vertically-reciprocating beam E is supported by and actuated through the four rods 60 e, that slide in bearings secured to frames A, and at their upper ends are rigidly secured to said beam, while upon the lower ends of the pair at each end of said beam is rigidly secured the cross-head F. (See Fig. 5.) Mid- 65 way between rods e is pivoted in F, at g, the pitman f, which at its upper end incloses the eccentric h, secured upon driving shaft i. The "throw" of said eccentric when shaft i is rotated produces the vertical reciprocation of 70 beam E and its action upon the cutting-dies. Said shaft is rotated by means of pulley G and clutch H, the clutch being rigidly secured upon the shaft, while the pulley is loose, except when forced into frictional contact with the 75 clutch, which contact is effected by means of treadles j, pivoted by rod m and connected, for convenience, by foot-board k, said treadles being habitually raised by the contractile force of springs l; and the treadles act upon the 80 pulley through rods n, connected at their lower ends with the treadles and at their upper ends with the horizontal arm of bell-crank p, pivotally supported on rear girt, C, the vertical arms of said bell-crank being pivoted to 85 the horizontal shipper-bar q, which is pivoted to shipper-lever s, having its pivotal fulcrum at t, while its lower forked end engages in a concentric groove in hub u of the driving-pulley, Figs. 1, 4, 6. Thus by pressing his 90 foot on board k the operator depresses the treadles, thereby, through rods n n, crank-levers p p, rod q, and lever s, forcing the pulley against the clutch and starting the machine.

To allow the operator to remove his foot from the treadle-board and yet insure a complete revolution of the machine, I pivot upon bar q a trundle, w, and I secure a cam, v, on a rod, e, Fig. 6, said cam and trundle being so arranged that as soon as the machine has been (through depressing the treadles) set in motion said cam, by pressing against the trundle, will, through bar q and lever s, hold the

5 pulley in contact with the clutch until the arrival of the beam E at almost its highest limit, when the cam no longer engages the trundle, and by the action of the lifting-springs l on the treadles the pulley will be held out of contact with the clutch till the operation is repeated.

10 To stop the machine when the beam is at its highest point, a brake, x, pivoted at y and raised by arm z of treadle rod m, acting against adjusting-screw 2, engages brake-wheel I on shaft i. Said brake falls by its own weight when released, leaving and freeing the wheel whenever, by depressing the treadles, arm z 15 of rod m is lowered, the treadles being rigidly secured to said rod m for that purpose, as the rod thereby acts as a rock-shaft.

15 One of the most important features of my invention is the method of counterweighting the vertically-reciprocating beam E, which, more especially in the larger machines, (nine-foot beams,) is, by reason of the great strain to which it is subjected, necessarily very heavy, and should therefore be not only in 20 perfect "balance" but also in perfect "cross-balance" as well. To insure both such balance and cross-balance, I form clutch H and brake-wheel I, each as much out of balance as equals one-half the weight moved vertically by eccentric 25 h, so that the united counterweighting of said wheel and clutch equals the weight of the beam and its rods. Such counterweighting of the clutch and wheel is effected by forming one part skeleton-like, as at 4, while the opposite side, as at 5, is solid and continuous, such solid portions being arranged on shaft i, diametrically opposite the throw of eccentric h, so that said solid portions are at the bottom 30 of their circuit when the beam is at its highest point; hence the machine performs its work without the violent shock and vibration that would otherwise result from rapidly reciprocating so heavy and inert a mass of metal as constitutes the beam and its direct coacting parts.

45 I claim as my invention—

1. In a beam cutting-machine, the combi-

nation of reciprocating beam C, its supporting-rods e, cross-heads F, pitman f, pivoted to said cross-heads and engaging the eccentrics of the driving-shaft, and a counterweighted clutch mechanism arranged on said driving-shaft, substantially as specified. 50

2. In a beam cutting-machine, the combination of beam E, its supporting-rods e, cross-heads F, pitman f, shaft i, with eccentrics h, and a counterweighted brake-wheel and clutch mechanism arranged upon the respective ends of said shaft, substantially as specified. 55

3. In a cutting-machine having a reciprocating beam and a clutch mechanism coacting therewith, the combination of treadles j, rods n, crank-levers p, rod q, lever s, pulley G, and clutch H, all combined and arranged to actuate and engage or release said clutch and pulley, substantially as specified. 65

4. The combination, with treadles j, rods n, crank-levers p, rod q, lever s, pulley G, and clutch H, of trundle w, secured in said rod q, and cam V, secured on rod e, whereby said clutch and pulley are automatically held in contact during a portion of their revolution, substantially as specified. 70

5. The combination of beam E, its supporting-rods e, cross-heads F, pitman f, eccentrics h, shaft i, and a driving mechanism on said shaft, substantially as specified. 75

6. The counterweighted clutch mechanism, its driving-shaft, the eccentrics arranged thereon, the pitman engaged by said eccentrics, 80 and the cross-heads through which the pitmen operate, substantially as specified.

7. In a beam cutting-machine, the combination, with beam E, of shaft I, pulley G, and counterweighted clutch H, mounted on said 85 shaft, and mechanism connecting said shaft and beam, whereby the rotation of said shaft through said clutch mechanism causes said beam to be vertically reciprocated, substantially as specified.

HENRY PARSONS.
